US00D726254S

(12) **United States Design Patent**
Kott(10) **Patent No.:** **US D726,254 S**
(45) **Date of Patent:** **** Apr. 7, 2015**(54) **LABEL SHEET**

(75) Inventor: **Marla Kott**, Richmond (CA)

(73) Assignee: **Illegible Products Ltd.**, Richmond (CA)

(**) Term: **14 Years**

(21) Appl. No.: **29/382,861**

(22) Filed: **Jan. 7, 2011**

(51) LOC (10) Cl. **19-01**

(52) U.S. Cl. **USPC D19/1**

(58) **Field of Classification Search**
USPC D19/1-8; 40/124.01-124.15, 672, 661, 40/726, 776, 617, 633; 229/72, 92, 92.1, 229/300-303; 283/72, 74, 75, 103, 105, 283/106; 206/449; D21/385; D20/10, 22, D20/27, 40, 42, 11; D14/435-437
